UNITED STATES PATENT OFFICE.

JOHN M. PERKINS, OF SOUTH BEND, INDIANA.

BOW-SOCKET FOR VEHICLE-TOPS.

SPECIFICATION forming part of Letters Patent No. 334,979, dated January 26, 1886.

Application filed November 2, 1885. Serial No. 181,606. (No model.)

To all whom it may concern:

Be it known that I, JOHN M. PERKINS, a citizen of the United States, residing at South Bend, in the county of St. Joseph and State 5 of Indiana, have invented certain new and useful Improvements in Bow-Sockets for Vehicle-Tops; and I do hereby declare the following to be a full, clear, and exact description of the invention, such as will enable 10 others skilled in the art to which it appertains to make and use the same.

My invention relates to vehicle bow-sock- 15 ets; and it consists of a socket made of wood or other suitable material having an inner and outer thin metallic lining.

It is desirable that a socket should be so constructed that a nail or screw can be put in it at any place to fasten the short bow that is placed over the top of the carriage, the ends 20 of which are inserted into the socket, and which must be secured there by screws or nails; also, in order to fasten the top prop onto the side of the standard directly over the socket by screws. If the metal socket is 25 made of malleable iron or heavy sheet-iron, the screw-holes are difficult to make, and when covered with veneer, or veneer and paper, or any textile material combined therewith, the outside covering of veneer will al- 30 most invariably split or separate from the metal; also, if the inside socket or lining is thick it will be so much higher than the core that the core must be built up flush with the socket before being wound with the veneer, &c., which is difficult to do and have a perfect job.

My plan is to make a double socket, or, rather, a wooden socket having thin inner lining and a thin outer metallic covering, the 40 metal being so thin that a nail or screw can be inserted through them simply by first perforating the outside socket with an awl.

My invention is illustrated in the accompa- 45 nying drawings; in which Figure 1 is an exterior view of the socket, and Fig. 2 a longitudinal section of the same.

In the drawings, A is the socket as a whole; B, the inner metal lining; C, the wooden part, and D the outer metal covering.

The outside metal and veneer through which 50 the screw passes before it gets to the inner socket will give sufficient hold to allow the screw to penetrate the inner metal by simply turning it with a brace or screw driver; also, a screw put through these metals will be held 55 so securely that there will not be any chance of the prop getting loose.

The difficulty with one well-known form of metal socket is that it is composed of a single socket of thin sheet-iron, and if the socket 60 is not filled, so that the screw enters that filling, the prop gets loose, and much difficulty is experienced from that cause.

Workmen often fail to take time to insert the top bows into the socket sufficiently deep, 65 and frequently get them too short, and to get the proper shape of top will only insert them a very short distance.

I make the outside socket, as a general thing, shorter than the inside one, so that it will not 70 come in sight below the valance in front or the quarters on the side when I use a japanned standard. When covered with leather, I put it on longer.

By my improvement a very desirable socket 75 is obtained, strong and stiff, one that will not split when the top bow is drawn in, and one that has the strongest kind of a bed for the screw whereby to hold the prop to the stand- 80 ard.

By the use of a thin inside socket, if de- sired, the bow can be made tapering and the core forced through the socket, leaving the combination so that it can be wound with ve- 85 neer, &c., and be made a solid structure with- out the trouble of building the core even with the socket, as is the case when the socket is made thick.

What I claim is—

A bow-socket consisting of an inner and 90 outer thin metallic lining, substantially as de- scribed.

In testimony whereof I affix my signature in presence of two witnesses.

JOHN M. PERKINS.
